UNITED STATES PATENT OFFICE

122,739

DESIGN FOR A DRESS

Harry Fried, Chicago, Ill.

Application July 29, 1940, Serial No. 94,000

Term of patent 3½ years

To all whom it may concern:

Be it known that I, Harry Fried, a citizen of the United States of America, residing in Chicago, county of Cook, and State of Illinois, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

HARRY FRIED.
